UNITED STATES PATENT OFFICE.

JOHN E. GIMPERLING, OF DAYTON, OHIO, ASSIGNOR OF ONE-FOURTH TO CLARENCE N. GREER, OF DAYTON, OHIO.

LOCKING DEVICE.

1,377,335.

Specification of Letters Patent. Patented May 10, 1921.

Application filed November 4, 1919. Serial No. 335,628.

To all whom it may concern:

Be it known that I, JOHN E. GIMPERLING, a citizen of the United States, residing at Dayton, in the county of Montgomery and State of Ohio, have invented certain new and useful Improvements in Locking Devices, of which the following is a specification, reference being had therein to the accompanying drawing.

10 This invention relates to locking devices, and more especially to anti-theft locks for securing certain levers of a motor vehicle to prevent unauthorized use or theft thereof. The invention is an improvement on the 15 anti-theft lock which forms the subject matter of Patent No. 1,318,443, issued to me October 14th, 1919, and has for its particular object to provide a simple, effective locking device, practically indestructible and 20 incapable of being tampered, and which may readily be secured to one of the foot levers, preferably the clutch lever, to lock the same in operative position.

An object of the present invention is to 25 provide a lock having the general characteristics of my earlier invention above referred to and which will be simpler and cheaper to manufacture and which will be of smaller dimensions and better proportions, and 30 therefore neater in appearance and more convenient to use.

In the form here shown my invention consists of an integral frame or locking block 35 preferably formed of sheet metal, and having a plurality of longitudinal channels extending therethrough to adapt the frame to extend over the stem of the foot lever and to properly position the same relative thereto and to the floor of the vehicle, suitable 40 means being provided to lock the device in position when the same has been adjusted relative to the lever.

A further object of the present invention is to provide one or more spring clamps in 45 connection with one of the longitudinal channels of the locking frame adapted to embrace the stem of the foot lever to hold the frame yieldingly in fixed relation to the lever to prevent side play or lateral 50 movement of the frame relative to the lever. It will be understood, however, that these clamps are not essential to the effectiveness of the locking devices, but are more in the nature of a refinement which effect aline-

ment of the frame when the same is applied 55 in its locking position on the foot lever.

In the accompanying drawings:

Figure 1 is a front elevation of my improved locking device with the locking hasp thrown open;

Fig. 2 is a side elevation of the same;

Fig. 3 is an end view;

Fig. 4 is a detail of one of the clamp springs;

Figs. 5 and 6 are plan and sectional views, 65 respectively, of a modified form of the locking device shown in Figs. 1 to 4; and

Fig. 7 is a detail of the device shown in Figs. 5 and 6.

As shown in the drawings the device consists of the frame or housing 1, substantially rectangularly shaped in cross section, and having three longitudinal channels 2, 3 and 4 formed therein to stiffen the frame and properly position the same relatively to the 75 foot lever, the channels as here shown also being rectangularly shaped in cross section.

The opposite ends 5-6 of the frame 1, as here shown, are inclined at different angles to the body of the frame to adapt the same 80 respectively to the tread of the foot lever and to the floor of the vehicle. It will be obvious, of course, that these ends may be inclined at any suitable angles to adapt the frame to the foot lever and floor of different 85 makes of automobiles and other motor vehicles, the relative angles here shown being for illustrative purposes only.

It will also be apparent that the channeled frame will be very rigid and possess 90 great strength, and being made of a heavy gage of sheet steel, will be practically indestructible.

In connection with the central channel 3, which is the one adapted to receive the stem 95 of the foot lever, one or more spring clamps 7 may be used, two clamps being here shown, to adjust the locking frame relative to the foot lever, that is to say, to properly position the frame relative to the foot lever and 100 to yieldingly support the same in said position. These clamps may be of any suitable construction, and may be spaced apart in the channel any suitable distance to best suit the conditions of construction.

To complete the frame as a locking fixture, a hasp 8 is secured to one side thereof in a manner to adapt the hasp to extend over the

channel 3, a staple 9 being secured in the frame on the opposite side of the channel to receive the end of the hasp. A suitable lock, such as a padlock, may be employed to lock the hasp in closed position and thus secure the frame to the lever in such a manner as to prevent operation thereof.

The hasp and staple may be secured to the frame in any suitable manner, preferably 10 by riveting the same to the metal. To prevent filing of the staple, the exposed portions thereof are preferably heat treated to harden the metal.

The form of locking device shown in 15 Figs. 5 and 6 and 7, relates to modified details of construction, the application and operation of the device relative to the foot lever being substantially the same as in the other form of the device shown in Figs. 1-4.

20 The modifications consist in making the entire device in two pieces, the hasp 10 being made detachable, having a bent end or tongue 11 adapted to project into a slot 12 formed in the face of the locking block on one side of the longitudinal channel 3, the opposite face of the block having a tongue 13 formed thereon integrally with the metal of the block, and adapted to coöperate with a slot 14 in the opposite end of the hasp.

25 Thus the hasp may be applied to the block without any riveting of parts, the tongue 13 being provided with an aperture 15 for the application of a suitable padlock to secure the closed hasp to the block.

30 The clamping springs 16 as shown in the modified construction are preferably formed integrally with the metal of the block, thus entirely eliminating the use of rivets in the locking device.

35 From the foregoing detail description the construction and application of my improved locking device will be apparent. It will be noted that the lock is small, of simple construction and neat appearance, practically indestructible and in all respects well adapted to the purposes of the invention.

Having thus fully described my invention, what I claim as new and desire to secure by Letters Patent, is:—

40 1. A locking device for a foot lever of a motor vehicle comprising a locking block adapted to be interposed between the tread portion of said lever and the floor of the vehicle to lock the lever in raised position, and having a longitudinal channel formed therein to receive the stem of the foot lever, and a spring clamp arranged in said channel to embrace said stem whereby to hold the locking block yieldingly in normal relation to said lever, and means to lock the

frame in said relatively fixed relation to said lever.

2. A locking device for a foot lever of a motor vehicle comprising a locking block 65 adapted to be interposed between the tread portion of said lever and the floor of the vehicle to lock the lever in raised position, and having a longitudinal channel formed therein to receive the stem of the foot lever 70 and a plurality of spring clamps arranged in said channel, one adjacent the opposite ends of the channel to embrace the upper and lower portions of said stem whereby to hold the locking block yieldingly in normal relation to said lever, and means to lock the frame in said relatively fixed relation to said lever.

3. A locking device for a foot lever of a motor vehicle comprising a locking block 80 adapted to be interposed between the tread portion of said lever and the floor of the vehicle to lock the lever in raised position, and having a longitudinal channel formed therein to receive the stem of the foot lever, 85 a slot formed in the face of the block adjacent the channel on one side and a tongue raised from its opposite face, and a hasp adapted to coöperate with said slot and tongue to close the open side of said channel.

4. A locking device for a foot lever of a motor vehicle comprising a locking block adapted to be interposed between the tread portion of said lever and the floor of the 95 vehicle to lock the lever in raised position, and having a longitudinal channel formed therein to receive the stem of the foot lever, a slot formed in the face of the block adjacent the channel on one side and a tongue 100 raised from its opposite face, and a detachable hasp having a tongue formed at one of its ends to enter said slot and a slot formed at its opposite end to receive the tongue formed on the face of the housing whereby 105 the hasp may be secured on the block to close the open side of said channel.

5. A locking device for a foot lever of a motor vehicle comprising a locking block adapted to be interposed between the tread 110 portion of said lever and the floor of the vehicle to lock the lever in raised position, and having a longitudinal channel formed therein to receive the stem of the foot lever, and one or more spring clamps formed integrally with the walls of the channel and inclined inwardly therefrom to embrace 115 said stem and to position the locking block relatively to said foot lever.

In testimony whereof, I affix my signature.

JOHN E. GIMPERLING.
